UNITED STATES PATENT OFFICE.

CHARLES ADAMS-RANDALL, OF NEW YORK, N. Y.

TELEPHONE APPARATUS.

No. 919,113.

Specification of Letters Patent. Patented April 20, 1909.

Application filed July 28, 1906. Serial No. 328,228.

To all whom it may concern:

Be it known that I, CHARLES ADAMS-RANDALL, a citizen of the United States, residing at New York, in the county of New York and State of New York, have invented new and useful Improvements in Telephone Apparatus, of which the following is a specification.

In telephony today, it is considered by many desirable and advantageous to adapt one telephone transmitter to the combined use of short and long distance transmission. To effect this as now practiced, the usual exchange circuit telephone transmitter is used in the ordinary way upon exchange circuits, and when long distance transmission is desired the exchange operator is notified, who then connects the "caller" and the "called" through the exchange switch-board, and in doing so "plugs" in an additional battery at the exchange provided for such special use, generally called a "booster", such increased battery at the central station giving an added current energy for the long distance transmission, by means of which conversation becomes possible over the increased main line distance with more or less satisfactory results. This plan, however, is not altogether satisfactory or convenient, and besides the amount of additional current energy is limited and not always adequate to the successful commercial transmission over the increased main line distance, which is also restricted or limited to the power or current energy that can be employed under this plan.

The object of the present invention is to overcome these disadvantages, defects and unreliability in long distance transmission, and to provide a more convenient and cheaper method and apparatus for effecting the reliable transmission of speech over long or short distances by using the same transmitter.

The invention consists broadly in an improved means for regulating and controlling at will at the transmitter or in the circuit of which it is a part, or in the main line circuit, the current energy required on a short or a long main line circuit for the reliable transmission of speech thereover; and, in an adjustable means or mechanism for regulating and controlling at the transmitter, or otherwise or elsewhere, the amount of current carried, varied and passing through the transmitter to adapt the same to the combined use on short or long main line transmission of speech.

The improved method is equally applicable to use with a local battery consisting of a number of cells in series to give the required voltage and having a proper amperage, or to the use of two or more similar independent batteries, or to the use of current from other sources, such as a central energy system, or from electric light mains in combination with suitable transformers.

The invention consists generally in regulating at the transmitter, or elsewhere, by any suitable means or mechanism, operated manually, semi-automatically, or automatically, the total current passing through the transmitter and over the main line, such means or mechanism consisting preferably of a device which is termed a "controller", and which may be located at the transmitter, or elsewhere. By the use of the controller the efficiency of the transmitter can be increased or decreased; the number of separate batteries used from a series of batteries can be determined; and the resistance of the transmitter increased or decreased, as required, whereby on either plan the total current passing through the transmitter or the circuit of which it is a part, and the total out-put of the effective current energy upon the main line circuit are absolutely controlled to any degree from minimum to maximum, and regulated to any length of circuit and in proportion to the distance or electric work to be done; all of which may be accomplished at the transmitter by the user at will, and independently of any intermediate battery and exchange operators.

In the drawings, Figure 1 is a diagrammatic view of a telephone apparatus embodying the features of the invention. Fig. 2 is a transverse section through a controller forming part of the apparatus. Fig. 3 is a transverse section of the transmitter. Fig. 4 is a diagrammatic view showing a modification in the source of electrical energy and connections. Fig. 5 is a diagrammatic view of a still further modification.

Similar characters of reference are employed to indicate corresponding parts in the several views.

The numeral 1 designates a metallic diaphragm or vibrator, to which is secured and insulated therefrom an electrode 2, preferably of metal, a wire or other connection 3 leading from this electrode to a binding screw 4. An annular elastic cup-shaped pad 5, of felt or other material, is secured to the

electrode 2, and in this cup-shaped pad granules of carbon or other variable resistance means 6 are held. The diaphragm 1 rests upon a suitable elastic cushion 7, preferably formed from a soft rubber tube, as shown, and arranged in a seat 8, formed in the metal base plate 9, the diaphragm 1 being clamped into position by two or more spring fingers 10 resting thereon at one end 10 and secured to the said base. Also secured to the base 9 is a cover 11, preferably of hard rubber, in which openings 12 are provided for the cup-shaped pads 5. A weighted adjustable flat spring piece 13 is secured to the 15 cover 11, and is arranged to close over the pad and granules, an adjusting screw 14 passing through the said piece 13 into the cover by means of which any desired pressure contact between the electrode 2, the 20 adjustable flat spring piece 13, and the granules 6 can be readily obtained. A suitable wire or other connection 13^a runs from the spring piece 13 to the screw 15 carried by the cover 11 and adjacent to the screw 4 also 25 held by said cover.

The foregoing description applies to the several fractional parts of the transmitter, of which four are shown, but any number of these fractional parts may be used to obtain 30 efficient results, each fractional part added increasing the power and effectiveness of the transmitter. To effect the use of these several fractional parts of the transmitter, singly or in multiple, a "controller" 35 is employed, which may be made in many ways, one form now preferred being shown in the accompanying drawings, and in which a shaft 17 is mounted upon and in suitable supports 16-16'. A metal cylinder 18, 40 partly covered with a hard rubber tube 19 or other suitable insulating material, is loosely fitted upon the shaft 17.

Secured to one end of the cylinder 18 is a toothed or ratchet wheel 20, which is hollowed out and contains a volute spring 21, one end of this spring being secured to the wheel 20 and the other end to the shaft 17. The shaft is also provided with a crank handle 22, and the rotation of the shaft by 45 means of said crank handle in one direction winds up the spring 21 and causes the cylinder 18 to turn, a catch-lever or dog 23 engaging the teeth of the ratchet wheel and preventing any backward movement of the said 50 wheel and the cylinder when the spring 21 is tightened or wound, as just explained. When the ratchet wheel 20 is engaged by the pawl or dog 23, a stop pin 24 on the cylinder 18 and a stop piece 25 coöperate to restrict 55 the backward movement of the cylinder when the ratchet wheel 20 and the dog or pawl 23 are disengaged. The dog or pawl 23 is in the form of a catch-lever and is pivoted at one 60 extremity in a support 26 secured to a block 65 27, attached to a frame upright or analogous

device 28 of the case or box containing the apparatus. Exterioly of the box inclosing the apparatus, a telephone hook 31 is located for practical use, and therethrough the crank handle 22 also projects. The catch-lever 23 has one terminal of a spring 29 secured to an intermediate point thereof and also to a part of the inclosing means for the apparatus, the said spring holding the catch lever up in operative position with relation 70 to the ratchet wheel 20. The free extremity of the catch lever is adapted to be engaged by a rod 30 secured to and depending from the telephone hook or switch lever 31. The telephone hook or switch lever 31 is suitably 75 pivoted, as at 32, and is engaged by one end of a spring 33, having its opposite terminal secured to an adjacent resisting means. This spring 33 operates to raise the switch lever when the telephone receiver is detached from 80 the latter, as will be readily understood.

The telephone receiver 34 is normally caught and held on the hooked extremity of the switch lever 31, and the movement of this lever in opposite directions is limited by 85 stop pins 35 and 36, respectively located above and below the same, or otherwise positioned to effect the same function. The switch lever 31 carries a contact piece 37, having an insulated member 38, upon which 90 contact springs 39 and 40 normally rest, the said springs being secured on an insulating block 41, the spring 39 being connected to the main line circuit through the receiver, terminal 58 to which the said wire 34' extends, and out to the main line 59, and spring 40 is connected to one pole of the battery or batteries by means of a wire 42 attached to a terminal 42', the latter having a battery wire 42^a. 100 Secured to the block 27 are contact springs 43, 44, 45, 46 and 47, which normally rest or bear upon the cylinder 18 or portions of the latter, as shown, the spring 43 contacting with the shaft 17 and connected to the lever 110 31, through the medium of a binding screw 48, by wire 49, the spring 44 contacting with the cylinder 18, and connected to the binding post or terminal 44' by a wire 44^a, the springs 45, 46 and 47 normally resting upon the insulation 19 and respectively connected to the binding posts 45', 46' and 47', by wires 45^a, 115 46^a and 47^a. Induction coils 44^b, 45^b, 46^b and 47^b are provided, there being as many, preferably, as there are fractional parts of the transmitter. Four batteries are also provided and designated by the characters B', B^a, B^b, B^c. The circuit connections between the batteries, transmitter and induction coils are preferably as follows:—from the 120 battery B' to terminal or binding post 48, from battery B^a to terminal or binding post 49, from battery B^b to terminal or binding post 50, and from battery B^c to terminal or binding post 51. The inside primary wires 125 130

of the coils 44^b, 45^b, 46^b and 47^b are respectively connected to the binding posts or terminals 52, 53, 54 and 55, the outside primary wires of these coils being connected respectively to the binding posts or terminals 44', 45', 46' and 47'. Connections are made from the fractional parts of the transmitter as follows: The first part or cup and its accessories are connected to the binding posts or terminals 48 and 52, the second part to binding posts or terminals 49 and 53, the third part to binding posts or terminals 50 and 54, and the fourth part to binding posts or terminals 51 and 55. The secondary wires of the induction coils are preferably connected up in multiple, the inside wires being connected to one lead or wire 56, which runs to the terminal or binding post 56', thence by wire 56^a to the lever 31, where said latter wire engages the binding screw 48. The outside wires of the secondary wires are connected to a lead or wire 57, which runs to the terminal or binding post 56', and from the latter to main line or ground wire 60. 25 All the parts, as shown, are in normal or first position.

The operation of the apparatus as thus far described is as follows: Upon removal of the telephone receiver 34 from the hook of the lever 31, the latter is released and moves upwardly through the operation of the spring 33, closing the line and local contact springs with the contact piece 37. The upward movement of the lever 31 also removes the rod 30 out of contact with the catch-lever 23, thus limiting the said catch lever and causing it to be free to engage with the ratchet wheel 20 by the action of spring 29. In this second position of the parts, the circuits are completed as follows: from battery B' by wire connection to the terminal or post 48, and thence by wire connection to the post 15 of the cover 11 of the transmitter, and thence through the electrodes and variable resistance to the binding screw or post 14, and from the latter to the binding post or terminal 52, induction coil 44^b and terminal or post 44'. From the terminal or post 44' the circuit is continued through the medium of wire 44^a connecting with the spring contact 44, thence to cylinder 18 to spring 43 which engages the shaft 17, wire 49 connecting with the switch lever 31, spring contact 40 engaging block 37 carried by said switch lever, wire 42 connecting with binding post or terminal 42', and wire 42^a to the other pole of the battery. This circuit gives the result that can be obtained from the use of the current from one battery connected up as shown and using one-fourth of the transmitter and one induction coil, and a consequent out-put of working current energy over and upon the main line from the one coil 44^b by wire 56 to the terminal or binding post 56', thence by wire 56^a, bind-

ing screw 48, lever 31, spring actuated contact 39, receiver 34, wire 34', binding post or terminal 58, to line 59, and by way of wire 57, terminal 57' to wire or ground 60, which current upon the main line, it has 70 been found in practice, is equivalent to that of the best telephone transmitters now used. If a more powerful current upon the main line is required, the handle 22 of the controller is turned a given distance and moves 75 the cylinder 18 to permit the spring contact 45 to coöperate therewith, this operation closing a second local circuit as follows: from battery B' to terminal or binding post 49 to a second fractional part of the transmitter, and therethrough by wire connection as shown to binding post or terminal 53, coil 45^b to terminal or binding post 45', spring contact 45, cylinder 18, spring contact 43, wire 49, to binding post or screw 85 48, lever 31, spring 40, and wire 42 back to battery as before, and by this means it will be seen that the working current will be doubled upon and over the main line by the use of two batteries and one-half of the transmitter and two coils. The power can now be still further increased in practically the same ratio, by turning the controller another step, closing the spring contact 46 with the cylinder 18 and permitting the use 90 of three batteries, and by turning the controller another step the spring contact 47 is brought into engagement with the cylinder 18, which will permit the use of four batteries, the four fractional parts of the transmitter, and the four induction coils or inductariums. In this latter adjustment, or what may be termed the fourth position, the maximum power upon the main line with a transmitter of this class, divided into four 100 parts, has been reached, and to augment this power still further a transmitter having eight, twelve, sixteen or more fractional parts will be required and can be used with obvious additions of coöperating battery 105 elements and inductariums and connections. To automatically restore the parts to first and normal position after use, it is only necessary to place the telephone receiver upon the hook, when the lever 31 will return to place or normal position, and the main and local circuits will be broken at the spring contacts 39—40, as set forth. The movement of the lever 31, due to the application thereto of the telephone receiver, depresses the catch-lever 23, through the medium of the rod 30 engaging said latter lever, and this depression of the catch-lever releases it from the ratchet wheel 20 which, with the cylinder 18, will be returned to normal position by the action of the coil spring 21, the return movement being limited by the stop pin 24 engaging the stop piece 25. It will be understood that the controller can be constructed in other ways to arrive at the same 115 120 125 130

result and without departing from the principle of the invention.

As shown by Fig. 4, the batteries B' , B^2 , B^3 and B^4 may be replaced by a battery B^5 , connected up in series parallel, and in this event it is desirable to have a larger single conductor or lead 61 from the battery, and connected to a "bus-bar" 62, from which several leads are connected to the binding 10 posts or terminals 48, 49, 50 and 51, and thereby to the transmitter binding posts, the leads between the bus-bar 62 and the terminal or binding posts 48, 49, 50 and 51 being designated by the numerals 63, 64, 65 and 66. 15 In this modification also a return wire 67 is used and connected at its ends to the battery B^5 and the binding post or terminal 42. When the battery B^5 is used, it will be understood, and as clearly indicated by the drawings, Fig. 4, that the batteries B' , B^2 , B^3 and B^4 are disconnected or are absent as a part of the apparatus. The total out-put of current upon the main line and through the transmitter can also be regulated in other ways, 20 one plan being to connect in the transmitter for maximum current, which can be varied in power by inserting at some place or places in the local circuit, as at 68, or in the line circuit, as at 69, an adjustable resistance or 25 rheostat 70, as shown by Fig. 1, the remaining part of the apparatus as illustrated by Fig. 1 being the same. This resistance can also be regulated by adapting the controller thereto.

30 In the use, in telephony, of "central energy" it is considered necessary to increase the internal resistance of the transmitter. With an instrument constructed in fractional parts, as herein shown and described, the internal resistance of the transmitter is increased by connecting the several fractional parts in series, as may be required to obtain the proper internal resistance, through the medium of the fractional parts, which may 35 be readily effected in various ways, to wit, the controller, Fig. 1, may be connected up in such manner that by its means the resistance of the transmitter can be varied from minimum to maximum at will, which is obtained 40 by connecting in severally, in series, the fractional parts of the transmitter, instead of different sections and batteries, as in Fig. 1 thereby controlling and regulating the current passing through the transmitter and at 45 the same time the effective current energy of the main line. Another means is illustrated by Fig. 5. In this latter figure, the central energy supply is designated by the numeral 72, and connected to the electrode 13 by wire 50 72, through the variable resistance and electrode 2 by wire 81 to switch S' to its contact or button s to the primary of the induction coil B by wire 85 back to the central energy supply 72, through the medium of a wire 84, 55 giving the resistance of one fractional part of

the transmitter, which is increased by connecting in another part of the transmitter, by changing the position of the controller, or, as shown, by changing the switch S' to s' and switch S^2 to its contact s^2 , the switch S^2 and 70 likewise switch S^3 being connected to the second and third fractional parts of the transmitter, and the fourth part of the fractional transmitter connected to a contact s^4 with which the switch S' co-operates, and also with 75 a contact s^5 , likewise positioned for engagement by the switch S^3 . When the switch S' is changed in position to engage the contact s' and switch S^2 is shifted to engage contact s^2 , the circuit will then be as before, to switch 80 S' by wire 81, connecting contacts s' with one terminal of the second fractional part of the transmitter, by wire 82, and by wire 83 connecting another terminal of the second fractional part of the transmitter with the switch 85 S^2 , and its button s^2 , and from the latter back to the battery 72 through the induction coil B by wires 85 and 84. Another part of the transmitter is added by changing switch S^2 to contact s^3 and switch S^3 to contact s^4 and 90 the remaining part by changing the switch S^3 to contact s^6 , when the fractional parts of the transmitter are all connected in series step by step, and the maximum resistance obtained. The rheostat 70, or other adjustable resistance, may also be used, as hereinbefore indicated, for the purpose specified, in connection with the circuits and controller shown by Fig. 5.

Having thus described the invention, what 100 is claimed, is:

1. In an apparatus for telephonic transmission of speech, the combination with a telephone transmitter provided with independent multiple parts insulated from each other and arranged to be connected up together in series, in whole or in part, of controlling means for regulating and determining the current-out-put of the transmitter to readily adapt the latter to be used efficiently 105 and practically upon circuits varying in length.

2. In an apparatus of the class set forth, the combination with a telephone transmitter provided with independent multiple parts insulated from each other and arranged to be connected up together in series, in whole or in part, of readily adjustable controlling means for increasing and decreasing the efficiency of the transmitter itself, whereby the transmitter can be adapted for either short or long main line circuits and the current-out-put regulated in accordance with the electric work to be done. 115

3. In combination with a telephone transmitter constructed in fractional or multiple parts insulated from each other and arranged to be connected up in series, in whole or in part, of a controlling device manually operative for regulating and determining the 120 125 130

necessary effective current energy to be transmitted over and upon main line circuits varying in length.

4. The combination with a telephone transmitter having fractional or multiple parts capable of independent operation, of means for regulating and determining the current energy passing through or over the transmitter and in proportion to the number of parts required for use to adapt the transmitter to the long or short main line circuits.

5. The combination with a telephone transmitter having independent fractional parts insulated from each other and arranged to be connected up in series, in whole or in part, of controlling means coöperating with the transmitter and operating through the latter for bringing into use one or more of the fractional parts to render the transmitter active and effective for the transmission of speech upon circuits varying in length.

6. In an apparatus of the class set forth, the combination of a telephone transmitter, a source of electrical energy, electrical connections between the said parts, a controlling means by which the current energy passing

over and through the transmitter and the circuit of which it is a part can be readily regulated and determined, as required, a telephone receiver, and means operative by the telephone receiver for setting the parts in operative position and for restoring the several elements to normal position at the time of termination of the transmission.

7. In an apparatus of the class set forth, the combination of a telephone transmitter, a source of electrical energy, means for regulating and determining the effective current energy required upon main line circuits of varying length and passing through and over the transmitter, a telephone receiver, and mechanism controlled by the telephone receiver for setting the elements in operative relation and for restoring them to normal position at the termination of the transmission.

In testimony whereof I have hereunto set my hand in presence of two subscribing witnesses.

CHARLES ADAMS-RANDALL.
